UNITED STATES PATENT OFFICE.

WILLIAM WALLACE KEMP, OF BALTIMORE, MARYLAND.

GAS BURNER.

Application filed January 13, 1927. Serial No. 160,908.

This invention relates to burners, and more especially to improvements in gas burners for use with baking ovens, stoves, retorts and the like. Certain features of 5 the invention are shown and described in applicant's co-pending application, Serial No. 15,315, filed March 13, 1925.

An object of the invention is to provide a burner construction whereby the volume 10 of mixed fuel and air admitted to the jet openings of the burner may be independently and selectively controlled.

A further object of the invention consists in arranging a burner casing and fuel manifold in sections and coupling or connecting the adjacent sections in such a manner that fuel can be delivered to the jet openings in the burner directly above the coupling.

Another object comprehends the provision of means associated with each of the coupling members for sealing the joints between the sections.

Other objects and advantages will become apparent from the following description 25 when taken in conjunction with the accompanying drawings.

Referring to the drawings in which is disclosed preferred embodiments of the invention.

Figure 1 is a fragmentary longitudinal 30 sectional view of one form of the invention.

Figure 2 is a view taken substantially along the line 2—2 of Figure 1.

Figure 3 is a detail sectional view of the 35 coupling shown in Figure 1.

Figure 4 is a longitudinal sectional view of a modified form of the invention.

Figure 5 is a view taken substantially 40 along the line 5—5 of Figure 4.

Figure 6 is a sectional view of another 45 modification.

Figure 7 is a sectional view taken along the line 7—7 of Figure 6.

Figure 8 is a fragmentary sectional view 50 of a still further modification of the invention.

Figure 9 is a view taken substantially along the line 9—9 of Figure 8.

Figure 10 is a fragmentary sectional view 55 of another form of the invention.

Figure 11 is a view taken substantially along the line 11—11 of Figure 10.

Referring to the drawings, and more particularly to Figures 1, 2 and 3, 10 designates a burner casing preferably formed in 55 sections and having in the top thereof a series of uniformly spaced jet openings 11. The casing 10 while shown of substantially cylindrical form in cross section may assume any desired shape and has positioned 60 therein a concentrically formed fuel or gas manifold tube 12, which preferably is composed of separate sections, but may be in a single piece, and communicates at either end with a fuel supply, not shown. The 65 fuel manifold tube 12 is provided with conical ports 13 diametrically positioned relative to the jet openings 11 so as to cause the mixed air and gas issuing from the tube 12 to be uniformly distributed to the jet 70 openings 11.

The supply of fuel through the ports 13 is preferably controlled by the needle valves 14 which extends through threaded bosses 15 formed in the bottom of the casing 10. 75 Each of the valves 14 is provided at its inner or upper end with a conical head 16 arranged to extend within the complementary formed openings 13, while the opposite end or base of the valve 14 has a kerf or 80 groove 17 arranged to receive any suitable tool such as a screw driver or the like for regulating the supply of mixed air and gas delivered to the interior of the casing 10 from the manifold 12. As the needle valves 85 14 are positioned exteriorly of the casing 10 and are independently operable, it will be seen that by selectively adjusting the various valves, the supply of fuel to certain sections may be varied without disturbing 90 the flame in other sections. Moreover, the valves 14 permit the fuel supply to be regulated to a very fine degree without the danger of the flame going out.

The manifold tube 12 is of smaller diameter than the interior of the burner 10 so as to form an annular space between these parts, thus insuring a proper circulation 95 of the fuel before it is delivered to the jet openings 11.

The adjacent end of the burner sections 10 as well as the manifold tube sections 12 are preferably connected to and supported by a coupling member or sleeve 18 which is positioned within the casing 10 and 100 formed with an exteriorly threaded surface 19 that engages complementary internal threaded surfaces in the adjacent ends of

the burner casing 10, while the abutting ends of the manifold tube sections extend within the coupling 18 and are supported thereby.

5 The jet openings 11 are preferably uniformly spaced apart and extend the length of the burner casing 10. In order that the jet openings directly above the coupling members 18 can be supplied with fuel, the 10 couplings are each provided with axially extending grooves 20 arranged on each side of an annular threaded portion 21 of the coupling, these grooves forming fuel passages which deliver the mixed fuel and air 15 to the jet openings 11 above the coupling, thus insuring an even and uniform flame being emitted throughout the length of the burner when the gas is ignited at any point within the casing.

20 The annular threaded portion 21 formed in the sleeve 18 is so positioned as to normally lie between the abutting ends of the sections to provide a packing for sealing the joint between these parts and thus precluding 25 the possibility of the fuel escaping from the burner otherwise than through the jet openings 11. Additionally, the threaded portion 21 of this coupling acts as a partition to divide the tube 10 into a series of 30 separate distribution chambers which may be independently and selectively controlled by the valves 14.

In the modified form of the invention illustrated in Figures 4 and 5, the fuel or 25 gas is delivered to the manifold chamber 22 in the casing 23 through a pipe 24. The casing 23 is preferably of cylindrical form in cross section and has a partition 25 so as to form a burner chamber 26 above the fuel 40 chamber 22. The chamber 26 has its upper surface formed with uniformly spaced jet openings 27, and is also divided interiorly into separate compartments by the transverse partitions 28.

45 The fuel or gas as it delivers to the manifold casing 22 is conducted to the burner chamber 26 through a series of conical ports 29 in the partition 25. The supply of fuel passing through each of the ports 29 is controlled by a needle valve 30 having at its inner end a complementary formed tapered head 31 arranged to fit in the opening 29 and a threaded shank which extends through a threaded portion formed in the 50 bottom of the casing 23. The ports 29 are preferably positioned relative to the partitions 28 so that the supply delivered to each compartment may be selectively controlled by the actuation of one of the needle valves 60 30.

In the form of the invention shown in Figures 6 and 7, the fuel or gas manifold tube 32 is shown positioned below the burner tube 33 and connected thereto at suitable 65 spaced intervals by the threaded nipples 34.

Each of the nipples 34 has a vertical bore 35 through which the fuel is delivered to the interior of the burner 33; the supply of fuel being selectively controlled by a needle valve 37 similar in construction and operation to the form of valves previously described. The burner tube 33 is divided into separate compartments by the partitions 38 preferably positioned between the nipples 34 and also has jet openings 39 through 75 which the mixed gas and air escape.

The form of the invention illustrated in Figures 8 and 9 is somewhat similar to that shown in Figure 1, and comprises a burner casing 40 arranged in sections and preferably of cylindrical shape in cross section. The fuel manifold tube 41 is also made up of sections and is provided with conical openings 42 diametrically positioned relative to the jet openings 43 in the burner casing 40. The supply of fuel or gas from the manifold tube 41 is exteriorly controlled by means of a threaded bolt 43 which has a tapered head 44 arranged to coact with the conical opening 42 for controlling the supply of fuel to the burner casing. The outer end or head 45 of the bolt 43 is of polygonal shape so as to be either manually operated or to receive a wrench or the like for causing the actuation of the valve. A locking nut 46 is preferably threaded to the bolt 43 and bears against the adjacent surface of the casing 40 to insure the proper positioning of the valve.

A coupling member or sleeve 47 has an exteriorly threaded surface 48 which engages a similar formed surface in the interior of the casing 40 adjacent the ends of each section. The coupling 48 is also formed with a counter-bored portion 49 at 10 each end thereof, so as to form shoulders that receive the adjacent ends of the gas manifold tube sections 41. The interior of the casing 40 adjacent the ends of each section is formed with an axially extending recess 49' which is interrupted at the point where the sections abut one another by an annular packing ring 50 formed of any suitable material, the lower portion of the ring 50 being arranged to fit in an annular recess 51 in the inner periphery of the casing 40.

It will be seen that by reason of the axial recess 49' formed in the inner wall of the casing 40, that means are provided for conducting the mixed air and gas to the burners positioned immediately above the coupling 47. The fuel manifold tube 41 is preferably maintained in a fixed and predetermined position relative to the burner casing 40 by means of the lugs or ribs 51' which radiate from the outer wall of the tube 41 and abut against the inner periphery of the tube 40 in the manner as shown in Figure 9.

It is to be understood, of course, that the 13

burner casing, as well as the fuel supply tube, may be composed of any number of sections which in construction and operation are substantially similar to the forms of the 5 invention previously described.

In Figures 10 and 11, there is illustrated a further embodiment of the invention, in which the burner casing 52 as well as the fuel delivery tube 53 are formed in sections, 10 each section being connected by a coupling or sleeve 54 which is exteriorly threaded so as to engage the threaded portion of the casing 52. The bore 55 of the coupling 54 is provided at each end with an enlarged 15 counter-bored portion that forms the shoulders 56 which receive the adjacent ends of the fuel tube 53. The interior of the casing 52 adjacent the ends thereof has an axially extending peripheral groove 57 which is in- 20 terrupted at the point of contact of the adjacent ends of the sections of the casing 52 by an enlarged annular rib 58 which acts as a packing or seal to prevent the escape of fuel at the point of contact of the burner 25 sections. The upper surface of the casing 52 has the jet openings 59 positioned so as to uniformly distribute the flame throughout the length of the burner.

The supply of mixed air and gas from the 30 manifold tube 53 is delivered to the interior of the casing 52, and conducted to the jet openings 59, through ports 60, preferably formed in the bottom of the tube 53, each of the ports having an exteriorly threaded 35 bushing or sleeve 60' which engages in the threaded openings formed in the bottom of the casing 52 and tube 53. The inward movement of the bushing 60' is limited by a flange 61 arranged to abut against the outer 40 surface of the casing 52. The inner end of the bushing 60' is formed with a vertical orifice 62 which delivers to a chamber 63 that communicates with the interior of the casing 52 through the radial ports 64. A 45 valve 65 controls the supply through the opening 62 and has a threaded shank portion 66 which terminates in an enlarged head 67, said head being positioned below the casing and outside thereof so as to be 50 manually actuated or operated by a suitable tool, to control the supply of fuel to the casing. A lock nut 68, is threaded to the shank 66 and engages the flange 61 of the bushing 60' so as to maintain the valve in 55 any predetermined position. In this form of the invention, it will be observed that the mixture of air and gas is conducted through the ports 62 and openings 64 into the interior of the casing 52 where it is distributed 60 to all the jet openings 59 including those above the coupling 54, the latter being supplied through the axial grooves 57 in the casing 52.

The packing ring 50 (Figure 8) and the 65 annular rib 58 (Figure 10) also act as par-

titions for dividing the sections of the burner casing into separate distribution chambers, each of which chambers, communicate with the gas manifold tube so as to be capable of operating either independently or simultaneously with the other sections of the burner.

It is to be understood that the various forms of the invention shown and described are merely illustrative of preferred embodiments, and such changes as fall within the purview of one skilled in the art may be made without departing from the spirit of the invention and the scope of the claims.

What I claim is:—

1. A gas burner comprising a sectional casing having jet openings, a fuel manifold tube within said casing and communicating therewith, a coupling connecting the adjacent sections, and means delivering the fuel 85 to the jet openings directly above the coupling.

2. A gas burner comprising a casing having jet openings, a fuel manifold tube within said casing and communicating therewith, said casing and tube being in sections, a coupling connecting the adjacent sections, and means delivering the fuel to the jet openings directly above the 90 couplings.

3. A gas burner comprising a casing having uniformly spaced jet openings, a fuel manifold tube within said casing and communicating therewith, said casing and tube being in sections, a coupling connecting the adjacent sections, and means delivering the 100 fuel to the jet openings directly above the couplings.

4. A gas burner comprising a casing having jet openings, a fuel manifold tube within said casing and having ports diametrically disposed relative to the openings in the casing, means for controlling the supply through said ports, said casing and tube being in sections, a coupling connecting the adjacent sections, means delivering the fuel 110 to the jet openings directly above the coupling, and means associated with the couplings for dividing the casing into separate distributing chambers.

5. A gas burner comprising a casing having jet openings, a fuel manifold tube within said casing and having ports diametrically disposed relative to the openings in the casing, means for controlling the supply 115 through said ports, said casing and tube being in sections, a coupling connecting the adjacent sections, means delivering the fuel to the jet openings directly above the coupling, and means associated with the couplings for dividing the casing into separate distributing chambers, said last mentioned means acting as a packing for the joint between the section.

6. A gas burner comprising a casing having jet openings extending the length there- 120

of, a fuel manifold tube within said casing and having ports diametrically positioned relative to the jet openings, a valve for each of the ports for controlling the supply therethrough, said casing and tube being in sections, a coupling connecting the adjacent sections, and means delivering the fuel to the jet openings directly above the couplings.

7. A gas burner comprising a casing having jet openings, a fuel manifold concentrically positioned within said casing and spaced therefrom, said manifold having ports diametrically disposed relative to the jet openings for delivering fuel to the casing, valves controlling the supply through said ports, said casing and manifold being in section, a coupling connecting the adjacent sections, said casing and coupling having a feed passage formed therebetween for conducting the fuel to the jet openings directly above the coupling.

8. A gas burner comprising a casing having jet openings, a fuel manifold concentrically positioned within said casing and spaced therefrom, said manifold having ports diametrically disposed relative to the jet openings for delivering fuel to the casing, valves controlling the supply through said ports, said casing and manifold being in sections, a coupling connecting the adjacent sections, means between the ends of the coupling dividing the casing into separate burner chambers, said casing and coupling having a feed passage formed therebetween for conducting the fuel to the jet openings directly above the coupling.

9. A gas burner comprising a casing having jet openings, a fuel manifold concentrically positioned within said casing and spaced therefrom, said manifold having ports disposed relative to the jet openings for delivering fuel to the casing, valves controlling the supply through said ports, said casing and manifold being in sections, a coupling connecting the adjacent sections, said coupling having an annular member dividing the casing into separate chambers, an axially extending feed passage on each side of said annular member for delivering the fuel to the jet openings directly above the coupling.

10. A gas burner comprising a casing having jet openings, a fuel manifold concentrically positioned within said casing and spaced therefrom, said manifold having ports diametrically disposed relative to the jet openings for delivering fuel to the casing, valves controlling the supply through said ports, said casing and manifold being in sections, a coupling within the casing connecting the adjacent sections, said coupling having an annular member dividing the casing into separate chambers and engaging the joints between the sections, axially extending feed passages formed on

opposite sides of the annular member for conducting the fuel to the jet openings directly above the coupling.

11. A gas burner comprising a casing having jet openings, a fuel manifold concentrically positioned within said casing and spaced therefrom, said manifold having ports diametrically disposed relative to the jet openings for delivering fuel to the casing, valves controlling the supply through said ports, said casing and manifold being in sections, a coupling within the casing connecting the adjacent sections, said coupling having an annular member dividing the casing into separate chambers, the ends of the casing sections having axially extending passages formed therein for delivering the fuel to the jet openings directly above the coupling.

12. A gas burner comprising a sectional casing having a series of axially extending jet openings, a fuel manifold tube within said casing and spaced therefrom, said tube having ports communicating with the interior of said casing, couplings connecting the adjacent sections, and means delivering the fuel to the jet openings directly above said couplings.

13. A gas burner comprising a sectional casing having a series of axially extending jet openings, a fuel manifold tube within said casing and communicating therewith, a coupling connecting the adjacent sections, said casing and coupling having an axially disposed passage therebetween for delivering the fuel to the jet openings directly above the coupling.

14. A coupling for connecting the adjacent ends of a sectional burner, said coupling having an axially extending groove in the surface thereof, to deliver fuel to the burner openings directly above the coupling.

15. A coupling for connecting the adjacent ends of a sectional burner, said coupling having an axially interrupted passage in the surface thereof, to deliver fuel to the burner openings directly above the coupling.

16. A gas burner comprising a sectional casing having jet openings throughout its length, a fuel manifold tube within said casing, and means connecting the adjacent sections of said casing, said casing and manifold tube forming a passage therebetween with which all said jet openings communicate.

17. A gas burner comprising a sectional casing having jet openings throughout its length, a fuel manifold tube within said casing, and means connecting the adjacent sections of said casing, said casing and manifold tube forming an annular space therebetween with which all said jet openings communicate, said connecting means

separating the annular space into non-communicating chambers.

18. A gas burner comprising a sectional casing having jet openings throughout its length, a fuel manifold tube within said casing and forming therewith an annular space, means connecting the adjacent sections of the casing and separating said annular space into non-communicating chambers, and means for supplying gas from adjacent chambers to jet openings in substantial alignment with the partition-like means.

19. A gas burner comprising a sectional casing having jet openings throughout its length, a fuel manifold tube within said casing, means connecting the adjacent sec-

tions of said casing, said casing and manifold tube forming an annular space therebetween with which all of said jet openings communicate, said connecting means separating the annular space into non-communicating chambers, said manifold tube having ports diametrically disposed relative to the jet openings for delivering fuel to the casing, each of the ports having a sleeve mounted therein provided with passages communicating with the manifold tube and the casing, and an externally actuated valve in said sleeve for controlling the fuel supply to the casing.

In testimony whereof I have hereunto set my hand.

WILLIAM WALLACE KEMP.
